UNITED STATES PATENT OFFICE

2,472,939

CRATE HAVING LIFTING MEANS

Claire A. Connolly, Detroit, Mich., assignor to the
United States of America as represented by the
Secretary of Agriculture

Application January 24, 1947, Serial No. 724,217

3 Claims. (Cl. 217—36)

(Granted under the act of March 3, 1883, as
amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to me of any royalty thereon.

This invention relates to packaging, and in particular to a rectangular wooden crate which is provided with hooks on the corners for the purpose of receiving ropes or the like for lifting the crate.

In general, according to the invention, a rectangular-shaped reinforced wooden structure designed for packaging heavy articles is provided with a notch at each upright edge, the notch being reinforced with a metallic plate fitted and secured to the structure at the edge and having a downwardly projecting tit located in the notch with clearance spaced below the tit, thus to provide a hook for receiving a rope for lifting the crate. The arrangement is such that the plate has no outwardly projecting portions, and very little material is cut away from the crate in providing the notch. Thus, a crate provided with the plates takes no more room than one without them, and very little strength is lost due to the notching.

For a more detailed description of the invention, reference may be had to the accompanying drawing, in which Figures 1 to 10, inclusive, each shows an edge of the crate with various modifications.

Referring to Figure 1, an upper corner of the crate is shown, the crate comprising a wooden structure provided with sides 11 and 12 and a top 13 secured to reinforcing pieces 15, 16 and 17. The structure thus far described is of conventional design. A notch 18 is cut in the edge near the upper corner, and a metallic plate 19 is fitted and secured to the edge in any desirable manner, as by screws 20. The metallic plate is provided with a cut-away portion 21 mating with the notch 18, and has a downwardly projecting tit 22 rigidly secured thereto and located in the notch to provide a hook. The plate is also provided with a flange overlying the top of the structure as illustrated. 23 illustrates a rope looped through the hook and used for lifting the crate. It is understood that each of the other edges of the crate is provided with similar devices for receiving the rope.

Figure 2 is similar to Figure 1, except that the notch 25 and plate 26 are slightly modified, as illustrated in the drawing.

2

Figure 3 shows a further modification of a notch 27 and plate 28.

In Figure 4, the structure is generally similar to Figure 3, except that the notch and plate are located below the top of the structure.

In Figure 5, the notch and plate are located at the upper corner, and are slightly modified over the forms shown in Figures 1, 2 and 3.

In Figure 6, the notch and plate are modified and are also located at the corner.

In Figure 7, the notch and plate are also located at the upper corner, and correspond closely to the showing of Figure 6. In this case, however, the downwardly projecting tit 40 is an integral portion of the plate.

In Figure 8, the notch and plate are located at the bottom corner, the tit being similar to the form shown in Figure 7.

In Figure 9, the structure is generally similar to that shown in Figure 4, except for a slight modification of the notch and plate.

In Figure 10, the structure is generally similar to that of Figure 5, except for a slight modification of the notch and plate.

Having thus described the invention, what is claimed is:

1. A packaging crate comprising a rectangular-shaped, reinforced, wooden structure provided at each upright edge with a notch and with a metallic plate fitted and secured to the edge and having a portion mating with the notch, said plate having no outwardly projecting portions and having a downwardly projecting tit located in the notch with clearance space below the tit thus to provide a hook for receiving a rope to lift the crate.

2. The crate as defined in claim 1, wherein the notch and plate are located below the top of the structure.

3. The crate as defined in claim 1, wherein the notch is near the upper corner of the structure and the plate is provided with a flange overlying the top of the structure.

CLAIRES A. CONNOLLY.
